WIRE LINE OPERATED CEMENT RETAINER
AND BRIDGE PLUG

Reuben C. Baker, Coalinga, and Clarence E. Burt, Los Angeles, Calif., assignors to Baker Oil Tools, Inc., Huntington Park, Calif., a corporation of California

Application October 10, 1936, Serial No. 105,046

14 Claims. (Cl. 166—13)

This invention relates to devices commonly termed cement retainers and bridge plugs which are utilized in bridging, cementing and other analogous operations in deep oil wells.

5 It is the principal object of our present invention to provide an improved cement retainer and bridge plug of the character referred to which is equipped with an improved tripping and setting mechanism whereby it may be run in the 10 casing of an oil well bore at the lower end of a wire line and tripped and set in the casing at any desired point therein by manipulation of the wire line from the derrick floor.

In practicing our invention, we provide a packer 5 body equipped with a slip assembly for anchoring it to the casing so that it will resist dislodgement from pressure above or below it in the casing. The packer body may be placed in the well casing and run in to the desired point at 10 the lower end of a wire line. The slip assembly is mounted on the body in an untripped condition and tripping and setting of the slips may be accomplished when the packer body reaches the desired point in the casing by manipulation 15 of the wire line from the derrick floor.

One form which the invention may assume is exemplified in the following description and illustrated by way of example in the accompanying drawings, in which:

0 Figs. 1 and 1a constitute a two-part longitudinal section through a cased well bore with our improved cement retainer and tripping apparatus positioned in the well casing with the parts thereof in the positions which they assume when the 5 device is being run into the casing and prior to tripping.

Fig. 2 is a transverse sectional view taken on line II—II of Fig. 1.

Fig. 3 is a transverse sectional view taken on line III—III of Fig. 1.

Fig. 4 is a transverse sectional view taken on line IV—IV of Fig. 1a.

Fig. 5 is a view similar to Figs. 1 and 1a showing the device after it has been actuated to trip 5 the slips.

Fig. 6 is a view similar to Fig. 5 showing the device after the slips have been set.

Fig. 7 is a view similar to Fig. 6 showing the manner in which the tripping mechanism is disconnected from the packer body and removed from the casing after the retainer and bridge plug has been set in the casing.

Referring to the accompanying drawings, particularly to Fig. 1a, 10 indicates a packer or what is commonly known as a cement retainer and

bridge plug. That is to say, the device may be used as a cement retainer or it may be used as a bridge plug. This device is cylindrical in cross section and of an overall external diameter, when in untripped condition, slightly less than the internal diameter of the well casing into which it is to be run and set. 5

The packer or cement retainer 10 includes an elongated hollow cylindrical body 11, the lower end of which is formed with a concentric circulating port 12 surrounded by a valve seat 14. Cooperating with this valve seat 14 to control the flow of fluid upwardly into the body 11 from below the same is a downwardly opening back pressure valve 15 here shown as of the poppet type. The valve 15 is fitted with an upwardly extending valve stem 16 having an enlarged head 17 at its upper end. The valve stem 16 is guided for vertical reciprocation in a valve stem guide 18 formed interiorly of the body 11. A spring 19 is interposed between the guide 18 and the enlarged head 17 and normally tends to maintain the valve 15 seated on the seat 14, thereby closing the main circulating port 12. It is obvious, however, that the valve 15 may be opened by fluid 20 pressure from within the body when the same exceeds the pressure in the casing below the packer or retainer 10. 25

It will be noticed that the body 11 is hollow and cylindrical and is formed with a lower bore 20, an upper bore 21 and an intermediate bore 22. The intermediate bore is reduced in diameter with respect to the upper bore 21 so as to form a bridging valve seat 23 between the same. The purpose of this seat will be hereinafter described. 35

A packer sleeve 24 formed of rubber or any other suitable or pliable material is arranged exteriorly on the body 11 and is anchored at its lowermost end to a fixed ring 25 which is bolted or otherwise secured to an annular flange 26 circumscribing the lower end of the body 11. The upper end of the packer sleeve 24 is anchored to a sliding ring 27 slidably fitting the exterior of the body 11. In unset position the exterior diameter of the packer sleeve 24 is less than the 40 45 interior diameter of the casing.

Arranged on the body 11 above the packer sleeve 24 is a double-faced cone 28 which is bored to a diameter just slightly greater than the external diameter of the body 11. The upper half 50 of the exterior surface of this double cone 28 is frusto-conical with its smaller diameter uppermost, while the lower half of the exterior face of the double cone 28 is frusto-conical with its smaller diameter lowermost. Formed centrally of 55

- the double cone member 28 is an interior annular groove 29 within which a latch ring 30 is positioned to engage annular latching serrations 31 formed exteriorly of the body to latch the body from movement downwardly relative to the cone 28 when the device has been set. When the packer 10 is in unset condition, the cone 28 is secured to the body 11 by one or more shear pins 32 as indicated in Fig. 1a.
- 10 Arranged about the upper cone face of the cone member 28 is a set of "up-pressure" slips A which are segmental and the interior surfaces of which are conical to coincide with and be complementary to the upper cone face. When the device is in untripped and unset condition, the upper set of slips A are connected to the cone 28 by shear pins 33, and in this condition the greatest external diameter of the set of slips A is less than the interior diameter of the casing.
- 15 Arranged about the lower cone face of the cone member 28 is a set of "down-pressure" segmental slips B. The interior surfaces of these slips are conical and coincide with and are complementary to the lower conical face of the cone member 28. When the device is in unset condition, the "down-pressure" slips B are connected with the cone by shear pins 34 in a position that the greatest external diameter of the set of slips B is less than the internal diameter of the casing.
- 20 It is obvious, of course, that when there is relative longitudinal movement between the slips A and B and the cone member 28, that the slips will be moved radially with respect to the body 11 due to the complementary cone faces between the slips and the cone.
- 25 To run the device in the casing, we provide a heavy mandrel 35, the lower end of which is of a diameter that it will project through the intermediate bore 22 and engage the upper end of the
- 30 valve stem 16 to overcome the pressure of the spring and unseat the valve 15. The opening movement of the valve is limited by a collar 36 formed on the mandrel at a spaced distance above its lower end and which seats on the bridging valve seat 23.
- 35 To enable fluid to pass upwardly through the intermediate bore past the collar 36 and into the upper bore 21 of the body 11 and thence upwardly, the lower end of the mandrel and the collar 36 are longitudinally grooved as illustrated most clearly in Fig. 4, the grooves being indicated by the numeral 37.
- 40 Secured in the upper end of the body 11 is a latching collar 38, the longitudinal bore through which is less than the external diameter of the collar 36 so that the latter cannot pass upwardly through the trip collar 38. The latter is latched in position from upward movement relative to the body by shear lugs 39 on a spring ring forming a part of the latching collar. The latching collar 38 is provided with vertical passageways 40 so that fluid may freely pass upwardly therethrough from the upper bore 21 of the body 11. It is intended that when removing the mandrel 35 or disengaging it from the body 11, that it be jarred upwardly so that the collar 36 will break out the latch collar 38 by breaking off the lugs 39, or by breaking off the upper end of the body 11. The mandrel may then be freely withdrawn upwardly from the body 11. This is done, of course, after the packer or retainer 10 has been firmly set in the casing.
- 45 For tripping the device, we provide a heavy hammer 41 which is arranged on the mandrel at a spaced distance upwardly from the packer 10.

This hammer 41 is bored longitudinally and slidably mounted on the mandrel and has a hollow cylindrical lower end of a diameter that it will strike the upper ends of the up-pressure slips A, when the hammer 41 is lowered on the mandrel 5 35. At its upper end the hammer is formed with three latching levers 42 which are pivoted thereto intermediate their ends as at 43. The upper ends of these levers are cam-like as illustrated. The lower ends of the levers 42 are inturned 10 to provide latching means which are complementary to latching grooves 44 formed longitudinally in the mandrel as most clearly illustrated in Fig. 1. Normally these latching levers 42 tend to remain in engagement with the latching grooves 44 so as to latch the hammer 41 on the mandrel at a spaced distance above the packer or retainer 10.

For releasing these latch levers, we provide a hammer trip member 45 which is cylindrical in 20 cross section and which is formed with a vertical slot in one side so that it may be slipped onto the wire line 46 which is connected to the upper end of the mandrel through a sub 47. The bore of the hammer trip 45 is sufficient to enable it 25 to pass over the sub 47 and the mandrel 35. The lower end of the hammer trip member 45 is so constructed that it will engage the cam-like upper ends of the levers 42 and tend to move such upper ends inwardly so as to release the 30 latching connection between the hammer 41 and the mandrel 35 so that the former may drop downwardly and impact against the upper ends of the slips A.

The hammer 41 is of considerable weight so 35 that its impact against the upper ends of the slips A will shear the pins 33 and move the slips longitudinally relative to the upper cone face of the cone 28, and thus trip the device. This relative movement between the slips and the cone 40 will cause the slips to move radially outward into contact with the casing so that upon subsequent upward movement of the cone relative to the slips, the latter will be jammed into setting position relative to the casing.

In operation of the device, it is constructed and assembled substantially as shown in the drawings and is lowered into the well casing. Due to the resistance of the fluid in the well casing, the packer 10 must be pushed downwardly therethrough. This is accomplished by the weight of the mandrel. It will be seen that when the mandrel collar 36 bears on the bridging seat 23, that the lower end of the mandrel will have engaged the upper end of the valve stem 16 and unseated the valve 15, so that fluid may flow upwardly through the body 11 past the mandrel and through the latching collar 38, so that no swabbing action will result.

The mandrel is, of course, connected at its upper end to the wire line 46 which extends, of course, upwardly to the surface and operated as in standard practice. When the packer or retainer 10 has reached the desired point in the casing, the feeding of the wire line 46 is stopped. The hammer trip member 45 is then applied to the wire line and allowed to lower to the position shown in Fig. 1 and engage the latch levers 42. Then by jerking the wire line the hammer trip member will release the latching engagement between the levers 42 and the mandrel, so that the hammer will drop and engage the upper ends of the slips A with such force as to shear the pins 33 and jam the slips downwardly between the upper cone face and the casing, thus tripping the 70 75

device. As soon as this has been accomplished, an upward strain is taken on the wire line 46 which places the collar 36 on the mandrel in contact with the lower end of the latching collar 38.

Continued upward movement of the mandrel 35 will, of course, be accompanied by upward movement of the body 11 and the cone 28 until the slips A are in set condition relative to the 10 casing, and the cone 28 cannot move any further upwardly. At this time the upward strain on the mandrel will be sufficient to shear the pin or pins 32 so that the body may continue to move upwardly and relative to the cone 28. Upon this 15 further upward movement of the body 11 the sliding ring 27 will engage the lower ends of the slips B, shearing the pins 34 and moving these slips upwardly relative to the cone 28 until they are tightly set relative to the casing. At this 20 time the sliding ring 27 can move no further upwardly but its lower end, which is connected to the bottom of the body 11, can continue to move upwardly with the body 11. This, of course, shortens the packer sleeve 24 and causes it to 25 expand in tight contact with the casing. When this expansion has been sufficient to cause such a seal between the body and the casing, the latch ring 30 will engage the latching serrations 31 and latch the body from downward movement 30 relative to the cone, and consequently to the slips and consequently latching the packer sleeve 24 in expanded position.

By exerting a jar on the mandrel 35 through the medium of the wire line 46, the lugs 39 on the 35 latching collar 38, or the upper end of the body 11, may be broken off and thus permitting the mandrel, the latching collar 38, the hammer 41 and the hammer trip 45 to be removed from the hole by pulling upon the wire line 46. At 40 this time, of course, the valve 15 will be closed so that cementing operations, if such are desired, may be carried on downwardly through the body 11, and after the cementing operations are completed, the valve 15 may close and act as a 45 back pressure valve.

If it is desired that the device operate as a bridge plug, a bridging ball, such as shown in dotted lines in Fig. 7, may be dropped downwardly through the casing into the body 11 to 50 seat on the seat 23 so as to close the body off from the flow of fluid therethrough, either from the top or from the bottom.

The body 11 and its associate mechanism is practically all of material that can be readily 55 drilled up so that, if desired, it may be drilled out of the casing after it has served its purpose.

From the foregoing it is obvious that we have provided a very simple and efficient cement retainer and bridge plug and tripping and setting 10 mechanism therefor, which may be run into any desired point in a well casing and then tripped and set at that point by manipulation of the wire line at the end of which it is run in, which tripping mechanism and wire line can be detached 15 from the device and readily removed from the casing.

While we have shown the preferred form of our invention, it is to be understood that various changes may be made by those skilled in the art 0 without departing from the spirit of the invention as defined in the appended claims.

Having thus described our invention, what we claim and desire to secure by Letters Patent is:

1. An apparatus of the character described 5 comprising a packer body adapted to be con-

nected to the lower end of a running in line and lowered into a well casing, slips assembled on said body in retracted position, and independent means movable with respect to said running in line adapted to move downwardly relative to the 5 slips on said body upon the same being positioned in a well casing to release the slips and move them to a set position.

2. An apparatus of the character described comprising a body adapted to be lowered into a 10 well casing at the end of a running in line, hammer means supported by said line in a position spaced upwardly from the body, slips assembled on said body in retracted position whereby they may travel through the casing with the 15 body, means separate from said running in line operative subsequent to the body reaching a desired position in the casing for releasing said hammer means to engage the slips and release them and to move them to a set position. 20

3. An apparatus of the character described comprising a packer body adapted to be connected to the lower end of a running in line and lowered into a well casing, slips assembled on said body and held in non-set position, means 25 separate from said running in line releasable from the top of the well adapted to move downwardly relative to the slips on said body and upon the same being positioned in a well casing to effect the release of the slips and move them 30 to a set position, and a normally unexpanded packing means carried by the body and capable of being expanded to form a seal between the body and the casing when upward movement of the body is imparted by upward movement of 35 said running in line subsequent to said slips being moved to an effective position.

4. An apparatus of the character described comprising a body adapted to be lowered into a well casing at the end of a running in line, hammer means releasably supported on said line in a position spaced upwardly from the body, slips on said body, means holding said slips in an un-set position and whereby they may travel through the casing with the body, means operative subsequent to the body reaching a desired position 40 in the casing for releasing said hammer means to engage the slips and release said holding means and move the slips to a set position, a packer sleeve on the body and normally contracted, said packer sleeve being adapted to be 45 radially expanded upon upward movement of the body relative to said slips after said slips have been moved to an effective position. 50

5. A device of the character described comprising a running in line, a hollow cylindrical body, means for detachably connecting the body to the lower end of the running in line, a cone mounted on the body, slips assembled on said cone and detachably connected therewith in a 55 normally unset position, slip engaging means latched to the running in line at a spaced distance above the body, and independent trip means adapted to be lowered over said line to engage and release said slip engaging means from 60 the running in line whereby said engaging means will descend and engage the slips and detach the same from the cone and move the same to a set position. 65

6. A device of the character described comprising a running in line, a hollow cylindrical body, means for detachably connecting the body to the lower end of the running in line, a cone mounted on the body, slips assembled on said cone and detachably connected therewith in an 70 75

unset position, slip engaging means normally latched to the running in line at a spaced distance above the body, trip means adapted to be freely dropped over said line to engage and release said slip engaging means from its latched position on the running in line whereby said slip engaging means will descend and engage the slips and detach the same from the cone and move the same to a set position, a packer sleeve on the body below said slips and capable of radial expansion to form a seal between the body and the casing upon upward movement of the body relative to said slips after the same have been moved to an effective position, said upward movement being effected by upward movement of the running in line.

7. A device of the character described comprising a hollow body having a passageway formed longitudinally therethrough, a valve in the lower end of said body closing said passageway, a mandrel adapted to extend into the body and engage said valve and open the same, the upper end of said mandrel being connected to a running in line, a plurality of slips assembled on the body, complementary cone faces on said slips and body whereby downward movement of the slips relative to the body will move them to an effective position with respect to the casing, a hammer latched to the mandrel at a spaced distance above the body, independent means releasable at the top of the well when the body has reached a desired position in the well casing to release said hammer from the mandrel so that the latter will descend to detach said slips from said body and move them downwardly relative to the body to a set position, means on the body and mandrel whereby upward movement of the mandrel relative to the body will be accompanied by upward movement of the body, said means when released by the exertion of upward force on the mandrel acting to detach the mandrel from the body.

8. A device of the character described comprising a hollow body having a passageway formed longitudinally therethrough, a normally closed valve in the lower end of said body closing said passageway, a mandrel adapted to extend into the body and engage said valve and open the same, the upper end of said mandrel being connected to a running in line, a plurality of slips assembled on the body, means normally holding said slips in an unset position, complementary cone faces on said slips and body whereby downward movement of the slips relative to the body will move them to a released and set position with respect to the casing, a hammer latched to the mandrel at a spaced distance above the body, independent means freely dropped into the well when the body has reached a desired position in the well casing to engage and release said hammer from its latched position on the mandrel so that the latter will descend to release said slips from said body and move them downwardly relative to the body to a set position, a packer sleeve on the body normally in contracted condition, means acting by upward movement of the mandrel subsequent to the moving of said slips to a set position to produce radial expansion of said packer sleeve into tight contact with the casing, said means being capable of being disrupted by manipulation of said running in line whereby the mandrel may be detached from the body and removed from the casing.

9. An apparatus of the character described

comprising a hollow body, a cone member on the body and having opposed cone faces thereon, a set of upper slips associated with one cone face, a set of lower slips associated with the other cone face, said slips being attached to said cone in an unset position, a running in line, a detachable connection between said line and the body whereby the latter may be run in at the lower end of the line, a hammer supported by said running in line at a position spaced upwardly from said body, optionally controlled means for releasing said hammer subsequent to the body reaching a desired position in the well casing whereby the hammer will descend and engage said upper slips and release them and move them to a set position, means on the body whereby subsequent upward movement of the body relative to said slips will release the lower slips and move them to a set position.

10. An apparatus of the character described comprising a hollow body, a cone member on the body and having opposed cone faces thereon, a set of upper slips associated with one cone face, a set of opposed lower slips associated with the other cone face, said slips being attached to said cone in an unset position, a running in line, a detachable connection between said line and the body whereby the latter may be run in at the lower end of the line, a hammer temporarily supported by said running in line at a position spaced upwardly from said body, means freely dropped into the well on the running in line, means for engaging and releasing said hammer when the body is at a desired position in the well casing whereby the hammer will descend and engage said upper slips and release them and move them to a set position, a packer sleeve on the body below the lower slips, a sliding ring connected to the upper end of said packer sleeve and slidably on the body whereby subsequent upward movement of the body relative to said upper set of slips will cause said sliding ring to engage and release said lower set of slips and move them to an opposed set position, after which said packer sleeve will expand upon continued upward movement of the body to form a seal between the body and the casing.

11. An apparatus of the character described comprising a hollow body, a cone member on the body and having opposed cone faces thereon, a set of upper slips associated with one cone face, a set of lower slips associated with the other cone face, said slips being attached to said cone in an unset position, a weighted mandrel adapted to project within the upper end of the body and to bear downwardly thereon, a freely movable hammer latched to said mandrel at a position spaced upwardly from the body, means for optionally unlatching said hammer from the mandrel when the body has reached a desired position in the well casing whereby the hammer will be released and will descend and engage said upper slips and trip the same and move them to opposed set position, and means whereby subsequent upward movement of the body imparted thereto by the mandrel will set the lower set of slips and move them to an effective position.

12. An apparatus of the character described comprising a hollow body, a cone member on the body and having opposed cone faces thereon, a set of upper slips associated with one cone face, a set of lower slips associated with the other cone face, said slips being attached to said cone in an unset position, a weighted mandrel adapted to project within the upper end of the body

and to bear downwardly thereon, a freely movable hammer latched to said mandrel at a position spaced upwardly from the body, means for optionally unlatching said hammer from the 5 mandrel when the body has reached a desired position in the well casing whereby the hammer will be released and will descend and engage said upper slips and trip the same and move them to an effective position, and means whereby subsequent 10 upward movement of the body imparted thereto by the mandrel will set the lower set of slips and move them to an effective position, said last-named means comprising a packer sleeve arranged about the body below the lower set of 15 slips, said packer sleeve adapted to set said lower slips and move the same to effective position and simultaneously radially expand into tight contact with the casing upon continued upward movement of the body.

20 13. An apparatus of the character described comprising a packer body adapted to be con-

nected to a running in line and lowered into a well casing, retracted means carried by said body for engagement with such casing and means releasable from above said body and downwardly movable with respect to said running in line and said retracted means to release said retracted means for engagement with such casing.

14. An apparatus of the character described comprising a packer body adapted to be connected to a running in line and supported thereby at any desired position within a well casing, slips carried by said body for engagement with such casing, means releasably holding the slips in retracted position, releasable means adapted to move downwardly relative to said slips, and 10 means operable from the upper end of the running in line to release said releasable means for downward movement whereby to release said holding means for setting said slips.
